HEINRICH C. W. SIEGMANN, OF GROSSENWIEDEN, GERMANY.

GATE FOR RAILWAY-CROSSINGS.

SPECIFICATION forming part of Letters Patent No. 673,929, dated May 14, 1901.

Application filed September 6, 1900. Serial No. 29,174. (No model.)

To all whom it may concern:

Be it known that I, HEINRICH C. W. SIEGMANN, a subject of the Emperor of Germany, residing in Grossenwieden, Empire of Germany, have invented a new and useful Gate for Railway-Crossings Adapted to be Operated Automatically by a Passing Train, of which the following is a specification.

In the accompanying drawings, which form an inseparable part of this specification, similar characters of reference refer throughout to similar parts, and in which—

Figure 1 is an elevation of a gate embodying my invention. Fig. 2 is also an elevation of the gate when closed. Figs. 3 to 12, inclusive, show on different scales details, &c., employed. Fig. 3 is an end and side elevation of the weight and its slides; Fig. 4, a plan thereof; Fig. 5, a like view with the parts in a different position; Fig. 6, a similar view with the parts in still another position. Fig. 7 is an elevation showing the weight on the draw-wire. Fig. 8 is a view showing a spring substituted for such weight. Fig. 9 is a diagrammatic view hereinafter more specifically described. Fig. 10 is an elevation of the pressure-bar. Fig. 11 is an elevation of the security device. Fig. 12 is a plan of Fig. 11.

The principle of the present invention is as follows: The opening and closing of the gate (formed of a bar adapted to drop into a horizontal position) is produced by altering the center of gravity of the said bar by a sliding weight which is moved by levers operated by a passing train. For this purpose a track for the sliding or actuating weight is fixed on the gate-bar extending on each side of the pivot of the said bar. Two endless draw-wires are attached to the said weight and are connected with levers, one of which latter is arranged at a suitable distance on the one side of the said gate and the other at a suitable distance on the other side of the said gate, both being located in such a manner that they are operated by a passing train from whichever direction the latter approaches, thereby moving the weight on its track and successively closing and opening the said gate as is desired.

In the form of construction shown in Figs. 1 and 2 a track 1 for the weight 2 is secured to the side of the gate-bar 3, and draw-wires $a a^x$ and $b b^x$ are connected with the said

weight. The manner in which the sliding weight is connected to the draw-wires is such that when the weight is moved by means of one wire the other wire remains unaffected. For this purpose two slides 4 and 5 are provided in or on the weight 2, having heads on each of their ends. (See Fig. 3.) The slide 4 forms a link in the wires $a a^x$ and the slide 5 a link in the wires $b b^x$. Each draw-wire is connected with a double-armed lever 6, which is mounted adjacent to the exterior or side of the rail in such a manner that when at rest—i. e., when the gate is open—it assumes a vertical position. The lever-arm pointing downward is connected with the draw-wires, while the lever-arm pointing upward ends in a tongue 7, the point of which in the rest position of the lever projects above the rail. Introduced into the draw-wires a^x and b^x are also graduated disks or pulleys 8 or such like, the purpose of which is to transmit the movement of the lever on a larger scale, as the course which the slides 4 and 5 have to travel is considerably longer than that of the lever. Thus, for instance, a train approaching from the left, the portion of the front wheel projecting over the side of the rail comes into contact with the tongue 7 or lever 6 on that side and moves the latter from the position shown in Fig. 1 to the position shown in Fig. 2. The draw-wires a must follow this movement of the lever 6 and must move in the direction of the arrow x , and consequently the slide 4, which is introduced into the draw-wires, must also move in the same direction. As soon as the slide 4 has traversed half its course, it drags, by means of its head, the sliding weight with it and moves said weight along its track 1 on the bar 3 also in the direction of the arrow x . (See Fig. 4.) The sliding weight 2 is thereby moved from the position shown in Fig. 1 to that shown in Fig. 2. As the weight of the sliding weight is greater than the difference in weight between the bar 3 and the balance-weight behind the latter, the center of gravity of the bar which has hitherto lain behind the pivot is transferred by the movement described to the other side of the pivot, and the bar 3 consequently drops to the horizontal position. (See Fig. 2.) The gate is thus closed. As the draw-wires $b b^x$ are connected by means of the slide 5 with the sliding weight

2 in the same manner as wires a^x and as the lever 6 always assumes the vertical position when at rest in consequence of its dead-weight, the draw-wires b remain totally unaffected, 5 because the slide 5, owing to its position in the middle, is not disturbed by the movement of the said weight 2. As soon as all the wheels of the train which project over the side of the rail, usually only those of the engine, have passed the tongue 7 of the lever 6 the latter assumes the vertical position again in consequence of its own dead-weight and moves thereby the slide 4, connected with it, by means of the draw-wires a into its former 10 position, the two slides 4 and 5 then having the relation to weight 2 shown in Fig. 5. The train then passing the closed gate and reaching the lever 6 on the other side displaces the latter in exactly the same manner 15 as it did the former one. The draw-wires b and the slide 5 are thus moved in the direction of the arrows y , (see Fig. 2,) and the slide drags the sliding weight 2 in the same direction—that is to say, moves it from the position shown in Fig. 2 to that shown in Fig. 1. 20 (See also Fig. 6.) The center of gravity of the bar is thereby transferred again to the other side—i. e., the back—and overbalancing again the weight of the bar raises the latter. 25 As soon as the train has passed the lever 6 last mentioned the latter swings back into the vertical position owing to its own dead-weight, so that the slide 5, which forms a link in the draw-wires b , is moved back again into its former central position. 30 (See Figs. 1 and 3.) The whole device is then ready again for the next train, and it is immaterial whether the latter approaches from the right or from the left, as it is clear that 35 the action of the device in both cases is exactly the same.

To prevent the gate from closing too quickly in consequence of the sudden movement of the lever 6 and possibly causing an accident, 40 it is advisable to provide a device such as, for instance, the roller 10, moving in a guide 45 9 in such a manner that in closing the gate the bar has to push the roller down and overcome the resistance of the counterweight 11, 50 the roller thus acting as a brake.

On railway-lines with express traffic the train would only displace the lever during a small fraction of a second and the draw-wires a^x and b^x would not be able to follow the sudden jerking movement in consequence of having to overcome their inertia. They would therefore inevitably break. To prevent this, it is advisable to make them of yielding nature. This can be done in different ways— 55 for instance, by hanging weights 12 on them, as shown on Fig. 7, or by providing springs 13, as shown in Fig. 8. On the lever being operated suddenly these devices are affected first, and then the effect of their reaction 60 opens or closes the gate. As hereby, however, in one direction the resistance of the sliding weight and the inertia of the draw-

wires have to be overcome, while in the other direction no resistance whatever has to be overcome—in fact the contrary influence 70 makes itself felt, the levers 6 having the tendency to reassume the vertical position independently in consequence of their dead-weight—it is necessary when such elastic devices are used to keep the lever 6 in its slanting position while the train is passing over and to release it again before the train has reached the lever 6 on the other side. The latter is necessary, as otherwise the train would not cause the opening of the gate 80 again. In Fig. 9 a device fulfilling this purpose is shown. In this case the lever 6 has a projection 15 or a finger, &c., which on the lever moving in the direction of the arrow lifts the triple-armed adjusted weight 85 lever 14 and engages a projection formed on the latter in such a manner that the lever 6 is held in the slanting position. To one side of the upward-pointing arm of the lever 14 a wire c is attached and to its other side the wire d . The outer end of each of these wires is secured to the periphery of a disk 16, while mounted loosely on the pivots of each of these disks is a lever 6^a , with a tongue 7^a. Each of these disks 16 is also provided 95 with a lug 17, against which the lever 6^a , moving on its pivot independent of the said disk, abuts when it is pressed down by the train, and thus causes the disk to move with it. The draw-wire c or d is thus wound on the 100 disk, and traction is exercised on the lever 14, which disengages the catch and permits the middle lever 6 to assume its vertical position again. (See Fig. 9.) As the projection 17 on the disk 16 is on the side of the lever farther 105 from the middle lever 6, it is clear that when the train approaches from either direction the first lever 6^a with which it comes into contact is moved, but does not affect its disk 16. The train operates the lever 6, which acts 110 upon the gate and is held in the slanting position until released by the train coming into contact with the second lever 6^a . The same action takes place beyond the gate, except when the purpose effected by the lever action 115 is the opening of the gate. The elastic device may be done away with by substituting for the lever 6 pressure-bars of considerable length. These are arranged movably along 120 side of the rail in such a manner that when the train approaches from the left one end of the bar is depressed, and when it approaches from the right the other end is depressed, the purpose thereof being to make the draw-wire 125 a or b move in the direction required by the direction of the train. A pressure-bar fulfilling this purpose is shown in Fig. 10. In its rest position the bar is pressed upward by means of springs in such a manner that its center part projects slightly above the rail, 130 parallel to the latter. The ends of the bar are hook-shaped and rest under suitably-shaped fixed hooks 19. Jointed to the ends of the bar are the elbow-levers 20, to which

the draw-wires a^x and b^x are fixed. A locking device is required in this case also, because otherwise as soon as the train has passed the center part the bar 18 might balance over 5 into the other position. In consequence of the considerable length of the rail-bar it is advisable to provide instead of one catch or lock-lever two elbow-levers 14. This catch device can be disengaged by means of the 10 same kind of levers as shown in Fig. 9.

To increase the security of persons and vehicles using the crossing, a further device can be provided near the gate and connected by 15 means of draw-wires with levers or the like placed considerably beyond the levers or pressure-bars hereinbefore described, and by which the approaching, closing of the gate, and arrival of the train are indicated independently before the train has reached the 20 device which operates the gate. Fig. 11 is a side view of a device of this kind, and Fig. 12 is a plan view thereof. It consists of a double-armed lever moving on the fixed pivot 21. At the end of the lever-arms 22 is a lantern 25, upon the glass of which a suitable warning is painted in legible characters. The lever-arm 23 forms a rail along which the sliding weight 24 can be moved by means of draw-wires e and f , connected with the device upon 30 which the train is to act. In the rest position of the lever shown in Fig. 11 the warning-signal is invisible. When the sliding weight 24 is moved toward the pivot 21, however, the lantern overbalances and appears behind an 35 opening in the casing 27.

Having now described my invention, what I claim as new, and desire to protect by Letters Patent, is—

1. The combination of a gate, a double-ended lever, slides, draw-wires connected to 40 the said lever and joined by said slides, a

weight through which said slides are movable, and connections between said weight and the gate, as set forth.

2. The combination of a gate, a double-ended lever, draw-wires connected to said lever, slides joining the said wires, connections between the draw-wires and gate embodying a sliding weight to which said draw-wires are connected and through which said slides are 45 movable, as set forth.

3. The combination of a gate, a double-armed lever, draw-wires connected to said lever, slides joining the wires, connections between the wires and gate embodying a sliding 55 weight to which said wires are connected, a guide on a fixed support, a roller movable in said guide and arranged in the path of the gate, and a counterbalance for said roller as set forth.

4. The combination of a gate, a double-armed lever, draw-wires connected to said lever, slides joining said wires, yielding devices in said wires and connections between the wires and the gate embodying a weight 65 through which said slides are movable, as set forth.

5. The combination of a gate, a double-armed lever, draw-wires connected to said lever, slides joining the wires, yielding portions 70 in said wires, connections between the said wires and the gate embodying a weight through which said slides are movable, a retaining device for said lever and a releasing device for said lever, as set forth.

In testimony whereof I have hereunto set my hand, in the presence of two witnesses, this 21st day of March, 1900.

HEINRICH C. W. SIEGMANN.
